ELECTRIC IRONER

Richard H. Cook, Milford, and Charles A. Berlepsch,
North Haven, Conn.

Application June 23, 1954, Serial No. 438,685

11 Claims. (Cl. 38—99)

This invention relates to ironing devices and more particularly to an iron of special construction which may be employed to iron portions of garments such as ruffles, pleats or sleeves. The device is intended to be detachably mounted by a suitable clamp upon a table, ironing board or the like, and the garment or portion of the garment to be ironed is drawn over the heated surface of the iron so as to be readily ironed into the proper shape and form.

As illustrated, the heat for the iron is supplied electrically and it is desirable in a device of this kind that the device be perfectly safe both from the standpoint of the electrical connections, and also from the standpoint of restricting the heated portions of the device to the ironing head itself, or that portion of the head which contacts the garment, in order that the remainder of the device shall not become excessively hot with consequent danger of discomfort to, or inflicting burns, upon the user.

To this end, the present device comprises a standard of hollow form and of insulating material such as Bakelite, for example, and the hollow metallic head is mounted at the upper end of this standard and secured thereto in such a manner as to conduct as little heat as possible to this standard. Also, the current-carrying wires leading to the head are carried to this standard through the lower end thereof so that there will be no danger of the wires coming in contact with the user of the device.

Means are also provided for controlling the degree of heat of the ironing head and this may be adjusted so that the upper limit may be varied in accordance with the material which is being ironed. This control is obtained by the use of a thermostat or temperature-responsive device, the active element of which is in contact with the metal of the head so as to be controlled directly by the temperature thereof.

One object of the present invention is to provide an ironing device of the character described which shall be relatively simple in construction and inexpensive to manufacture, and, at the same time, be particularly serviceable in use.

Another object of the invention is to provide an ironing device of the character described wherein a hollow standard of insulating material is employed to support a metallic ironing head, the head being mounted at the upper end of the standard, and current-carrying wires are enclosed within the standard.

A still further object of the invention is to provide an ironer of the character described having a hollow insulating standard supporting at its upper end a hollow metallic ironing head and having a clamp member at its lower end comprising a pair of cooperating clamp jaws, one of which is formed integrally with the insulating standard, and the other is spring-pressed into engagement with the first.

Still another object of the invention is to provide an ironer of the character described having an insulating standard supporting at its upper end a hollow metallic ironing head of particular shape and design, an electric heating element being provided within the head, and tem-

2

perature-responsive means also provided within the head to control the heat of the iron.

To these and other ends the invention consists in the novel features and combinations of parts to be herein-after described and claimed.

In the accompanying drawings:

Fig. 1 is a sectional view of an ironer embodying our invention;

Fig. 2 is a horizontal sectional view of an ironer head on line 2—2 of Fig. 1;

Fig. 3 is a sectional vertical view on line 3—3 of Fig. 1;

Fig. 4 is a horizontal sectional view on line 4—4 of Fig. 3; and

Fig. 5 is a horizontal sectional view on line 5—5 of Fig. 3.

To illustrate a preferred embodiment of the invention, we have shown in the drawings an electric iron comprising a hollow standard 10 which may be of electrical insulating material such as Bakelite, for example. At the lower end of this standard is provided a laterally projecting jaw or clamp member 11 formed integrally with the standard of the same material, which clamp member is adapted to rest upon the upper side of a suitable support 12 such as an ironing board or table.

Cooperating with the clamping jaw 11 is a second clamping jaw 13 secured to the lower end of a sleeve 14. This sleeve 14 is slidably mounted upon a tubular member 15 which extends upwardly into the lower end of the standard. The latter is provided with a transverse web 17 and the tubular member 15 is provided with screw threads 18 at its upper end, and is secured to the web 17 by the nuts 19 and 20 received upon the threads.

The tubular member 15 is provided with an upwardly facing shoulder 21 and the upper end of the sleeve 14 is provided with an opposite downwardly facing shoulder 22. A spring 23 surrounds the tubular member 15 between it and the sleeve member 14 and acts between the shoulders 21 and 22 to urge the sleeve member 14 upwardly and thereby urge the clamping member 13 toward the cooperating jaw member 11.

It will be seen that with this construction, it is only necessary to grasp the lower jaw 13 and pull it downwardly, as shown in Fig. 1, against the tension of the spring 23 in order to release the clamping jaws 11 and 13 from the support 12 and, of course, the device may be detachably clamped upon the support by a similar procedure.

A hollow ironing head of special form and design is mounted at the upper end of the hollow standard 10. The head as shown is formed in two similar mating halves 25 and 26, which may be joined together along the median plane 27. Below the upper hollow portions, the two halves of the head are so formed as to provide substantially circular flanges 28 and 29 connected by a relatively small stem 30. It will be noted that the flanges 28 and 29 are snugly received in the upper end of the hollow standard and the upper flange is provided with a shoulder 31 adapted to seat upon the upper end of the standard.

The upper flange 28 is also provided with diametrically opposite recesses 32 and 33 within which are secured by the screw 34 the upper ends of narrow spring members 35 and 36. The lower ends of these spring members are secured to the standard by the screws 37 and 38. With this construction, it may be noted that there is a minimum amount of contact between the metallic head portion of the device and the insulating standard so that the latter will not become overheated, and this is particularly true in view of the fact that the connecting springs will transmit a very small amount of heat to the standard or the screws 37 and 38.

The two halves of the ironing head are secured together by the screw 34, and are also held against rela-

tive displacement by a pin 40 inserted in reversing openings 41 in the halves of the flange 29 and also by a pin 42 inserted in similar openings 43 (Fig. 2) in the nose of the hollow head.

The head portion of the device is shown more particularly in Figs. 1, 2 and 3, and it will be noted from Figs. 1 and 3 that the metal of the head, which is preferably aluminum, is relatively thick at its upper surface, as shown at 44, but gradually decreases in thickness upon its side edges so that it is relatively thin at its lower portion, as shown at 45, for example, adjacent the flange 28, so that heat from the heating element, which will be hereinafter described, will be absorbed to a greater extent by the thicker upper wall 44 of the head. This will result in this wall being maintained at a higher degree of heat than the side walls 45 which is desirable both due to the fact that the upper surface of the head will be the one which is principally employed in use, and also due to the fact that a smaller amount of heat will be transmitted to the hollow standard.

As illustrated, the hollow head is of substantially circular form in horizontal cross section at its rear end and also of substantially circular form in cross section at the nose or front end, the rear end being described upon a considerably larger radius, and the side walls are substantially tangent to the two circles so that the larger rear portion of the head merges into the pointed nose along smooth lines, both in the vertical dimension and horizontal dimension of the head. Thus there are no breaks or sharp corners presented which facilitates the use of the device.

Mounted within the hollow head is an electrical heating element 48 which is, roughly, of hollow heart-shape form, as shown in Figs. 1, 2 and 3, and current is supplied to this heating element through wires 49 and 50 which pass downwardly into the standard 10 and through the tubular member 15.

Mounted within the heating element is a temperature-responsive switch consisting of two contact members 51 and 52. The member 52 is a bimetallic temperature-responsive element so that upon heating, it will move upwardly away from the contact member 51 against the spring 53. The position of the lower contact member 51 may be regulated by a rod 54 rotatably mounted in the suitable openings in the flanges 28 and 29 of the head member, this rod being threadedly engaged in a bracket or strap 55 secured to the base 56 of the contact members. A stop 57 is secured upon the rod 55, the end of which engages the depending end 58 of the bracket 55 so as to limit the turning of the rod 54 to a little less than one complete revolution.

The rod 54 may be rotated by a manually engageable turn-button 60 secured at the lower end of this rod and projecting through the case in the opening 61 provided for this purpose. The member 60 and the adjacent portion of the case may be provided with suitable indicia to indicate the degree of heat permitted by the adjustment of the rod 54. The upper end of this rod is provided with a nose portion 62 bearing against the lower contact member 51 to adjust the position thereof.

The contact members 51 and 52 are supported by the base 56 which in turn is secured to a bracket 63 formed integrally with the hollow head. In this construction, the temperature-responsive element 52 is in direct contact with the upper wall of the hollow head to receive heat therefrom and so as to be controlled by the heat of the ironing surface. It will be understood that when the thermostatic element 52 is heated, it will tend to bend upwardly against the tension of the spring element 53 and become disengaged from the contact member 51 and thus cut off the current.

The lead wire 50 is connected to the lower contact member 51, while the upper contact member 52 is connected to a lead wire 64 which enters the heating coil and completes the circuit with the wire 49.

While we have shown and described some preferred embodiments of our invention, it will be understood that it is not to be limited to all of the details shown, but is capable of modification and variation within the spirit of the invention and within the scope of the appended claims.

What we claim is:

1. An ironer for ruffles, pleats or the like, comprising a vertically disposed hollow standard of insulating material open at one end, a hollow metallic ironing head seated on the open end of said standard at the upper end thereof, said head having a portion received within the standard with a flange on said portion and relatively narrow strap-like members secured to the flange and standard to secure the head in place, and means for heating said head.

2. An ironer for ruffles, pleats or the like, comprising a vertically disposed hollow standard of insulating material open at one end, a hollow metallic ironing head seated on the open end of said standard at the upper end thereof, said head having a portion received within the standard with a flange on said portion and relatively narrow strap-like members secured to the flange and standard to secure the head in place, and means for heating said head, said members being disposed within the standard.

3. An ironer for ruffles, pleats or the like, comprising a vertically disposed hollow standard of insulating material open at its upper end, a hollow metallic ironing head seated on said standard at the upper end thereof, said head having a neck portion projecting into the standard and fitting snugly therein, spaced securing means attached to the neck portion and to the standard at the inner surface thereof to secure the head to the standard, and means to heat said head.

4. An ironer for ruffles, pleats or the like, comprising a vertically disposed hollow standard of insulating material open at its upper end, a hollow metallic ironing head seated on said standard at the upper end thereof, said head having a stem portion received within the standard with a flange on said portion and relatively narrow strap-like members secured to the flange and standard to secure the head in place, means for heating said head, said head comprising two substantially equal half portions meeting on a vertical plane, and an electrical heating element mounted within the hollow head.

5. An ironer of the character described comprising a hollow standard of insulating material, a hollow metallic head mounted on the upper end of said standard, said standard having an integrally formed upper clamp member projecting laterally from its lower end, a lower operating clamp member, means attaching said lower clamp member to the standard comprising a hollow cord-carrying member secured to the standard and projecting therefrom, a sleeve slidably surrounding said last-named member and having the lower clamp member secured thereto, and spring means supported by the standard and acting against the sleeve to urge said lower clamp member toward the upper clamp member.

6. An ironer of the character described comprising a hollow standard of insulating material, a hollow metallic head mounted on the upper end of said standard, said standard having an integrally formed upper clamp member projecting laterally from its lower end, a lower operating clamp member, means attaching said lower clamp member to the standard comprising a hollow cord-carrying member secured to the standard and projecting therefrom, a sleeve slidably surrounding said last-named member and having the lower clamp member secured thereto, and said sleeve and cord-carrying member having opposing shoulders and a compression spring on said hollow cord-carrying member within the sleeve and acting against said shoulders to urge said clamp members together.

7. An ironer of the character described comprising a

hollow standard of insulating material, a hollow metallic head mounted on the upper end of said standard, said standard having an integrally formed upper clamp member projecting laterally from its lower end, a lower cooperating clamp member, said standard having a transverse web member intermediate its ends, a tubular cord-carrying member secured at its upper end to said web member and projecting from the lower end of the standard and having a shoulder thereon, a sleeve slidably surrounding the tubular member and having the lower clamp member secured at the lower end thereof, and a spring within and acting at one end against a portion of the sleeve and at its other end against said shoulder to urge said lower clamp member toward the upper clamp member.

8. An ironer of the character described comprising a hollow standard of insulating material, a hollow metallic head mounted on the upper end of said standard, said standard having an integrally formed upper clamp member projecting laterally from its lower end, a lower cooperating clamp member, said standard having a transverse web member intermediate its ends, a tubular cord-carrying member secured at its upper end to said web member and projecting from the lower end of the standard, a sleeve slidably surrounding the tubular member and having the lower clamp member secured at the lower end thereof, said tubular member and sleeve having opposing shoulders, and a compression spring acting between said shoulders.

9. An ironer for ruffles, pleats or the like, comprising a vertically disposed hollow standard of insulating material open at its upper end, a hollow metallic ironing head heated on said standard at the upper end thereof, said head having a depending stem extending into the

standard, and a flange member on the stem fitting snugly within the standard, and spring members secured to the standard and to the flange member to secure the head in place.

- 5 10. An ironer of the character described, comprising a hollow standard of insulating material open at its upper end, a hollow metallic head seated on the upper end of said standard, said head having a downwardly projecting portion extending into the standard, said portion comprising a stem and a pair of spaced flanges thereon, said flanges fitting snugly within the standard, and relatively narrow strap-like members secured to one of said flanges and to the standard to secure the head in place.
11. An ironer as in claim 10 having an electrical heating element mounted within the head, a temperature-responsive element adjacent the upper wall of the head, electric switch means adapted to be opened by said element, and means to control the opening of said switch means comprising a rotatable controlling member extending through said flanges, and said standard having an opening in its side wall through which a part of said controlling member projects.
